[57] CLAIM

The ornamental design for a hose quick connector with housing, as shown and described.

DESCRIPTION

FIG. 1 is a top plan view of a hose quick connector housing showing my new design, the bottom being identical in appearance;

FIG. 2 is a right side elevational view thereof, the left side being a mirror image of that shown;

FIG. 3 is a front elevational view thereof; and,

FIG. 4 is a rear elevational view thereof.

The broken-line disclosure of internal features is for illustrative purposes only and forms no part of the claimed design.
